HOLDER FOR CASSETTES OR THE LIKE

Asa P. Ruskin, 865 West End Ave.,
New York, N.Y. 10025

Filed June 27, 1972, Ser. No. 266,665

Term of patent 14 years

Int. Cl. D3—01

U.S. Cl. D87—1 D

FIG. 1 is a front perspective view of a holder for cassettes or the like showing my new design;

FIG. 2 is a rear elevational view thereof;

FIG. 3 is a front elevational view on an enlarged scale;

FIG. 4 is a side elevational view thereof in an open position, the opposite side being a mirror image of the side shown;

FIG. 5 is a bottom plan view thereof; and

FIG. 6 is a front elevational view thereof, in an open position.

I claim:

The ornamental design for a holder for cassettes or the like, as shown and described.
